US00D772835S

(12) **United States Design Patent** (10) **Patent No.:** **US D772,835 S**
(45) **Date of Patent:** **** Nov. 29, 2016**

(54) **CELLULAR PHONE**

- (71) Applicant: **LG ELECTRONICS INC.**, Seoul (KR)
- (72) Inventors: **Byeongwook Kim**, Seoul (KR); **Hyoni Kim**, Seoul (KR); **Youngho Kim**, Seoul (KR)
- (73) Assignee: **LG ELECTRONICS INC.**, Seoul (KR)
- (**) Term: **14 Years**
- (21) Appl. No.: **29/503,398**
- (22) Filed: **Sep. 25, 2014**

(30) **Foreign Application Priority Data**

Mar. 26, 2014 (KR) 30-2014-0015025

- (51) LOC (10) Cl. **14-03**
(52) U.S. Cl. **USPC ..... D14/138 AB**

(58) **Field of Classification Search**

USPC ..... D14/138 AA, 138 AB, 138 AD, 138 G, D14/138 R, 341, 345, 203.7, 248, 496; D10/65; 361/679.27
CPC .. G06F 1/1652; G06F 1/1616; G06F 1/1618; G06F 1/1624; H04M 1/0222; H04M 1/0254; H04M 1/0256

(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view in an open state thereof;

FIG. 9 is a front view in an open state thereof;

FIG. 10 is a rear view in an open state thereof;

FIG. 11 is a left side view in an open state thereof;

FIG. 12 is a right side view in an open state thereof;

FIG. 13 is a top view in an open state thereof; and,

FIG. 14 is a bottom view in an open state thereof.

The broken lines shown in the figures that are immediately adjacent to the shaded areas and define unshaded regions represent the bounds of the claim. All other broken lines, i.e. the features within broken line boundaries, are directed to environment. The broken lines form no part of the claimed design.

1 Claim, 13 Drawing Sheets
